14 Claims. (Cl. 120—14.3)

1

The present invention relates to a mechanical pencil wherein the lead is progressively advanced by pressure on a spring-recoil, plunger-like head, and wherein leads of any one of a number of colours or qualities may be automatically selected.

A main object of the invention, in fact, resides in the provision of a pencil of the "plunger" type noted above having means for selectively feeding leads of any one of a number of colours or qualities.

Another important object is to provide a mechanical pencil having improved means for advancing a lead into writing position.

Still another important object resides in the provision of a pencil having improved means for gripping a lead in writing position.

And yet another object is to provide a pencil as set forth above having means guarding against inadvertent releasing of all the leads contained therein.

Or, as will be appreciated from the foregoing, it is the general object of the invention to provide a mechanical pencil of an all-round improved character and having an exceedingly simple "press+release" type of operation.

Or, as will be equally well appreciated, further important objects of my invention are to provide improved means for selecting any one of a number of types of leads, improved means for advancing leads, and improved means for gripping same in writing position, any of which means are adaptable for usage in any mechanical pencil of "press-release" action.

Other objects and advantages will become apparent, or be further pointed out, in the description to follow.

As an example, and for purposes of illustration only, preferred embodiments of my invention, indicating alternative forms of construction, are shown in the annexed drawings, wherein:

Figure 1 shows a longitudinal view, partly in section, of one form of my invention having conventional lead-advancing means;

Figure 2 shows a longitudinal mid-sectional view of the pencil of Fig. 1, with the mechanism in released, lead-gripping position;

Figure 3 shows a view similar to Fig. 2 only with the mechanism in advanced position;

Figure 4 shows a view similar to Fig. 3 except that the pencil has been inverted prior to advancement of the mechanism;

Figure 5 shows an opened-out, perspective view of some of the parts of the pencil of Fig. 1 and indicates the co-operation thereof;

Figure 6 shows a detail longitudinal section

2

through the bottom portion of the lead-advancing member or tube broken away from Fig. 5;

Figure 7 shows a detail, longitudinal section through the lead-gripping tip of the pencil of Fig. 1;

Figure 8 shows a longitudinal view, partly in section, of a pencil of alternative construction having improved lead-advancing means;

Figure 9 shows an enlarged, mid-sectional view of the bottom portion of the pencil of Fig. 8;

Figure 10 shows a section along the line 10—10 of Fig. 9;

Figure 11 shows a section along the line 11—11 of Fig. 9, and

Figure 12 shows a section along the line 12—12 of Fig. 9.

Referring now to the drawings, wherein the same reference characters denote corresponding parts throughout, the mechanism of the pencil is seen to be enclosed in a casing C of any suitable shape and dimensions. In the upper portion of the casing may be disposed a lead-selecting means from which the leads will be guided through an advancing mechanism to a device at the bottom of the pencil adapted to grip and hold a lead in position for writing. It is therefore convenient to describe the pencil of Figs. 1 to 7 in this manner, that is, from top to bottom.

The lead-selecting mechanism is one in which any one of several styles of leads may be chosen for advancement to the subsequent devices. Thus it is essential first to have a cartridge in which the several qualities or colours of leads may be stored in separate compartments. Such a cartridge 15 is provided herein and is best shown in Figures 1, 2 and 5, having a tubular casing 16 open at one end and provided with a plurality (in this case, four) of compartments separated by radial partitions 17. This cartridge is normally located near the top of casing C and has a closed upper end 18.

Disposed respectively above and below the cartridge, and adapted to receive either end of the latter, are the cap 19 of the pencil, and the magazine or lead-advancer 20. Each of these members has an open cylindrical end (22, 23) in which cartridge 15 is insertable. A plurality of spurs 24 spaced evenly around each end of the cartridge co-operate with longitudinal slots 25 and 26 in the open ends of the cap and magazine and tend to hold the three members against relative rotation when assembled. The slots 25 in the open end 22 of the cap are of such a length that spurs 24 are engaged near the closed, inner ends thereof, whilst the slots

26 in the cylindrical portion 23 of the magazine receive spurs 24 near their open, outer ends. As a result of this arrangement, the cap will engage the cartridge more firmly and will carry the latter therewith when rotated. Such rotation, as the lower spurs 24 slip at regular intervals into and out of engagement with slots 26, will bring one or other of the cartridge compartments into position registering with the lead-releasing means described below. Therefore, any indicating means such as 30 on the top or sides of cap 19 will show which colour or quality of lead is in position for use. Figure 5 shows that, if desired, the slots 25 and 26 may be notched at 32, at appropriate locations for determining the position at which the spurs will register properly.

Since the pencil is adapted to operate by pressure on cap 19, the latter will project from the top of casing C a sufficient distance to allow adequate displacement of the moving parts of the mechanism. Once the cap has been rotated so that the desired type of lead is in position for use, it is required that all further control of the lead be exercised by simply pressing the cap inward and releasing it to spring outward.

The lead-releasing means so operated is disposed in the upper end of the magazine 20 and consists of a fixed gate 35 and a movable or rotatable gate 36. The former of these is seen to consist of a flat circular plate from which one radial segment, of dimensions the same as those of a single cartridge compartment, has been removed. Lugs or spurs 38 project from the circumference of the plate and are engageable in the bottom of slots 26 (under the open end of the cartridge) to hold gate 35 in fixed position. Just below the bottom of slots 26 the cylindrical magazine 20 is stepped inwardly, and the flanged upper end 39 of the movable gate rests on the shoulder 40 so formed. For a considerable distance below this point magazine 20 extends longitudinally of casing C and the upper portion of the former rotatably carries the body of the movable gate. This body is cylindrical in outline and has a radial segment longitudinally removed therefrom on the side normally opposite the opening in gate 35. However, upon the cap being displaced downwardly, suitable means cause the movable gate to swing into a position registering with the fixed gate so as to allow the leads in the selected cartridge compartment to fall into the magazine.

Preferred means for causing such displacement of gate 36 (best shown in Figs. 2 and 5) consist of a helicoidal groove 41 formed in the outer surface of the gate and a pin 42 projecting fixedly in from casing C (through vertical slot 43 in the magazine) in engagement with the groove. When cap 19, and hence the cartridge and magazine, is pressed downward, the pin moves upwards relative to downwardly moving gate 36 and causes rotation of the latter. This brings the gates into registering position with one lead compartment and permits the leads to fall into the magazine (Fig. 3). As the cap recoils upward, the mechanism returns to the position of Figs. 1 and 2.

The foregoing describes the means for selectively releasing any one of a number of colours or qualities of leads into the magazine. Obviously the embodiment of such means herein shown and described could be widely varied without departing from the scope of the invention, which seeks to provide a mechanism oper-

ated by simply rotating the cap for selection purposes and pressing same for releasing purposes. The cartridge 15 could obviously be inverted if it is desired that no leads whatever be released therefrom in operation, and it is only a minor alteration to provide two or more such cartridges in longitudinal series, the pencil casting being lengthened accordingly and only the lower cartridge being utilized.

10 The mechanism for positively advancing the leads from the magazine is disposed at the lower end of the latter and co-operates with the lead-gripping tip of the pencil. Thus the magazine is reduced to a substantially smaller outside-diameter near the bottom thereof and projects downward in an elongated, hollow tube 45. The outer surface of the magazine is stepped sharply inward in two successive steps to meet the said tube, and exterior shoulders 46 and 47 are accordingly formed. Inside the magazine, in order to facilitate downward feeding of leads, the wall curves smoothly in towards the bore of tube 45.

15 At a distance below shoulder 47 (Fig. 2) approximately equal to the stroke of cap 19 an exterior flange 48 is formed on tube 45. Also at this point the inner wall of casing C slopes inwardly at 49 and is shaped with a depressed, inwardly-extending shoulder 50 upon which rests the outwardly-flared upper extremity 51 of a sleeve 52. This sleeve spacedly surrounds the lower portion of tube 45 and extends down the inside of casing C.

20 The lower portion of tube 45 is slotted (Fig. 3) longitudinally as at 53 to form tweezers or claws of three or more sections. These tweezers sections tend to spring outwardly but, when the mechanism is in the position shown in Figs. 1 and 2, are squeezed together by sleeve 52 which is stepped inwardly at this point and has an extremity 54 of reduced diameter. Another sleeve 55, having a diameter equal to that of the larger portion of the sleeve 52, is threaded to the extremity of the latter and extends down towards the tip of the pencil. Here casing C tapers inwardly and finally terminates in a rim 56 against which an outwardly-projecting shoulder 57 on sleeve 55 is adapted to abut. The lower portion of this second sleeve has an exterior flush with casing C and tapers down similarly towards tip 58. The interior diameter of the sleeve remains constant down to an inwardly-stepped shoulder 59 formed therein below the end of the casing. Below this, sleeve 55 continues down to tip 58 where it is formed with an outwardly flared or inside beveled extremity 60 for reasons set forth below.

25 The tip or lead-gripping member of the pencil is best shown in Figure 7. It has a flanged upper rim 61 sitting on an elongated tubular body 62 with a tip proper 58. The latter has a bevelled upper surface corresponding to the lower end of sleeve 55 and tapers down to a substantially small outside diameter. The lower portion of tube 62, together with the tip proper, is slotted longitudinally to form tweezers or claws as in the case of the tube 45. This set of claws also tend to spring outwardly and are normally squeezed tightly only by means pressing together the co-operative bevelled surfaces referred to above. Such means preferably consist of a spring 63 compressed between the rim 61 of the tip member and shoulder 59 of sleeve 55. When the claws are so squeezed (Fig. 1 and 2), the space therebetween is very limited and no lead will fall by

gravity. On the other hand, just above the tip proper the inside diameter of the body 62 widens out somewhat as at 65, and will allow free passage of a lead to this point. It may also be found desirable to form an exterior flange such as 66 on the body 62, intermediate the ends thereof, for purposes of guiding and balancing movement of the tip.

To complete the lead advancing and lead gripping mechanisms, a recoil spring 67 for the cap stroke is compressed between flange 48 (of tube 45) and the inwardly-stepped extremity 54 of sleeve 52. In addition, a ball 68, disposed freely above the upper rim of sleeve 52, will place a certain restraint upon the movements of the mechanisms as described below.

The operation of the pencil of Figs. 1-7 is as follows. A number of leads of the particular type desired are released into the magazine as noted above. The pencil mechanisms are then in the position best shown in Figure 3 with the tweezers at the bottom portion of tube 45 displaced below the lower extremity of sleeve 52 and hence free to spring outwards. However, owing to the position of ball 68, which abuts the under surface of shoulder 67 and prevents further downward movement thereof, the bottom of tube 45 does not extend far enough to touch or displace rim 61. The lead is accordingly free to introduce itself in the bore of the pencil down as far as the point 65 of the tip, but will go no further. If the cap is now released, spring 67 drives the mechanism upward and the tweezers portion of tube 45 is once more squeezed by sleeve 52. However, the claws are so formed that they will not grip a lead properly on withdrawal, and so the pencil takes up once again the position of Fig. 2 with leads aligned down to point 65. Pressure on cap 19 will now cause the clawed portion of 45 to force the leads forward, and, despite the force of spring 63, will pass a short length of lead past 65. Upon withdrawal of the propelling mechanism, the projecting portion of lead will be securely gripped by the tip claws and the length of that portion of lead in position for writing may be increased by simply pressing and releasing the pencil cap, alternately.

If now it is desired to change the lead or to remove all leads from the pencil, it is only necessary to invert the latter so that ball 68 falls out of its position under shoulder 67 (see Fig. 4). If the cap 19 now be pressed inward, there will be no restraint to the distance which tube 45 will move and the latter will accordingly have a stroke adequate for the purpose of displacing tip 68 outwardly against the force of spring 63. When this occurs, the tip tweezers will diverge as they protrude from the pencil until the leads are free to move from tip to magazine. Since at the same time the gates of the lead-releasing mechanism are in registering position so as to open one of the cartridge compartments, all the leads will return to the cartridge from whence they were previously selected.

It is clear from the above that this form of construction of my invention is a sound and practical embodiment of the principles set forth and fulfills the foregoing objectives. However, it must be emphasized again at this point that the particular details of shape and size and arrangement of parts have been selected, in this specification, with an eye to clarifying the principles and operation of the invention rather than to define the scope thereof. For practical purposes,

some of the parts may be found to be better constructed in several units, rather than as a single integral unit. And, of course, the converse is true. It will be noted, for instance, that the fixed gate 35 is provided with bevelled edges on the radial borders of its segmental opening. This is to prevent breaking or abrasion of the leads when the cartridge is rotated. Other features of the construction will become equally apparent upon examination.

An alternative form of construction which has the nature of an improvement over the pencil described above is shown in Figs. 8 to 12. The modifications are confined to the lead propelling and gripping mechanisms below the magazine.

As before, magazine 23 is stepped sharply inward at the bottom thereof to form shoulders 46 and 47, and extends for a distance equal to the stroke of the mechanism as a tube 45. In the present instance, the bottom of tube 45 may be shaped with a socket 70 into which a second tube 71, of similar cross-section, is inserted. The latter extends down the bore of the casing, has a plurality of longitudinal slots 72 through its lower portion, and terminates in a threaded extremity 73.

Spacedly surrounding tube 71, and having an outwardly flared rim 75 resting on casing shoulder 50, is a sleeve 76. This latter has an upper portion similar to sleeve 52 of the first constructional form, and a threaded mid-section 78 of reduced diameter. Sleeve 55 is connected to sleeve 76 at the threaded section, and below this point the latter member is formed with a plurality of projecting claws or tweezers-sections 79. These claws 79 will tend to protrude through slots 72 in order to grip a lead carried in the bore of the tube.

Sleeve 55 extends down towards the pencil tip in the same manner as previously described, and carries slidably therein the lead-gripping mechanism including a tip member. The latter has the usual tip proper 58 at the end of a tubular body 62 upon which is formed an exterior flange 66 and a crown 60. This crown differs somewhat from rim 61 in having preferably an outwardly-tapering bore at the top thereof, below which is formed a threaded socket 81 adapted to receive the lower extremity 73 of tube 71.

The inside diameter of the tip is restricted at 65 in order to prevent inadvertent passage of lead beyond this point. Moreover, a spring 63 is provided, as before, between the crown 60 and sleeve shoulder 59 to urge withdrawal, and hence closure, of the tip members.

The recoil spring 67 for the propelling mechanism is located between the projecting socket 70 and inwardly-stepped threaded section of sleeve 76.

The operation of this alternative construction of lead advancing and gripping mechanisms is now apparent. When the mechanism is advanced by pressing on cap 19, the leads so released are free to introduce themselves into the mechanism down as far as restricted point 65 in the tip. This is because pressure on the cap displaces tube 71 downwardly and hence brings the upper edges 82 of slots 72 into contact with the inner surfaces of claws 79. The spring claws are thus forced outwardly and will allow the lead to pass. Moreover, ball 68 in its position under shoulder 47 limits the mechanism to a short stroke, which prevents flange 66 from issuing beyond the bottom rim 60 (of sleeve 55) to release claws 58 of the tip.

When pressure is released and the mechanism is allowed to recoil, the tube 71 moves first to release the claws 79 which then grip the lead firmly. As the entire mechanism recoils further, the end of the lead so gripped projects beyond the withdrawing tip-claws 58 until these are closed in tightly gripping position by contact with the inner bevelled edge 60 at the bottom of sleeve 55. If the lead need be advanced further, it is only necessary to repeat the operation described.

In order to return all leads to their cartridge compartment, the pencil is inverted and operated as in the previous constructional form, ball 68 again falling out of its obstructing position. The tip member is thereby displaced far enough out of the pencil so that its claws 58 open and release the lead.

It will be apparent from the foregoing that the lead-advancing and lead-gripping mechanisms, or the two alternative combinations thereof herein shown and described, may be used in conjunction with any lead-supplying means to comprise a completely operable automatic pencil. It is equally true that the selective lead-supplying means disclosed herein may be profitably employed with any lead propelling mechanism of the "press-release" type. The use of successively stepped shoulders on the bottom of the lead magazine in conjunction with an obstruction 68 is also felt to be an advance in the art in that it permits the "press-release" system to perform a different function when the pencil is inverted than that carried out normally.

It may be noted that in the second form of construction the shoulder 48 on tube 45 has been replaced by a socket 70, and that a second tube 71 replaces the extension used in the first form. This alteration is only for the purpose of fabrication since it is easier to make the two parts rather than to form them integrally. Similar alterations might be carried out in any of the individual parts or mechanisms embodied herein, and it will therefore be understood that I do not limit myself to what is shown or described, but that various changes might be made in the size, shape and arrangement of all members, or combinations thereof, without departing from the spirit of the invention if within the scope of the subjoined claims.

Having thus described my invention, what I claim is:

1. In a mechanical pencil of the type wherein a lead is advanced to writing position by pressing and releasing a spring-recoil mechanism of limited longitudinal movement, and wherein a lead magazine in said mechanism is adapted to feed the leads so advanced; the combination therewith of means for selectively releasing into the magazine leads of any one of a plurality of qualities, said means comprising an elongated hollow cartridge frictionally engaging the magazine at one end so as to move longitudinally therewith and rotatably with respect thereto, partitions arranged in said cartridge to define a plurality of longitudinal lead-storing compartments, the cartridge open at the end adjacent the magazine, and fixed and rotatable gate means disposed transverse the open cartridge end having apertures therethrough adapted to be brought into registration with each other and with a single cartridge compartment when said mechanism is longitudinally displaced by pressure; whereby the leads of any predetermined cartridge compartment may be released into said magazine.

2. In a mechanical pencil combination as

claimed in claim 1, the closed end of said cartridge having a cap projecting from the non-writing end of the pencil, and means on said cap indicating the particular quality of lead in any cartridge compartment, whereby the pre-selection of the compartment to be positioned for registration with said gate means is facilitated.

3. In a mechanical pencil combination as claimed in claim 1, said gate means comprising: a fixed gate disposed transverse the magazine adjacent the open cartridge end having an aperture therethrough registerable with any one of the said compartments, a second gate having an aperture therethrough of similar cross-section to the first aperture but normally held out of communication therewith, said second gate rotatably and non-slidably held in said magazine adjacent the first gate, and means in said pencil for moving said second gate rotatably to bring said apertures into registration when the spring-recoil mechanism is longitudinally displaced by pressure.

4. In a mechanical pencil combination as claimed in claim 3, said means for moving the second gate comprising: a longitudinally-extending shell-like apron on the second gate having a helicoidal groove formed thereon, and a projecting pin rigidly fixed in the pencil in engagement with said groove.

5. In a mechanical pencil combination as claimed in claim 1, said spring-recoil mechanism enclosed in an elongated, axially-bored casing tapered inward at the writing end of the pencil, the bore of said casing having an outwardly-flared bevelled surface at the tapered casing extremity, an outwardly-sprung chuck in the tapered end portion of the casing, jaws on said chuck shaped exteriorly so as to co-operate with said bevelled surface and grip a lead tightly when the chuck is urged into said casing, and spring means for urging the chuck into the casing.

6. In a mechanical pencil combination as claimed in claim 5, said spring-recoil, lead-advancing mechanism adapted to displace said chuck outward for jaw-opening purposes when displaced by pressure to the full longitudinal extent, and gravity-operated means disposed in said casing to obstruct the mechanism when the pencil is held normally and to free the mechanism when the pencil is inverted.

7. In a pencil of the type having an elongated axially-bored casing tapered inward at the writing end, and a spring-recoil lead-advancing mechanism movable longitudinally for a limited distance in said casing, and wherein a lead is advanced by alternately pressing and releasing said mechanism; said casing having an outwardly-flared, bevelled surface formed at the tapered extremity, a chuck slidable in the tapered portion of the casing having projecting, outwardly-sprung jaws, means for urging said chuck inward relative to the casing, and said jaw shaped exteriorly to co-operate with said bevelled surface and grip a pencil lead tightly when the chuck is held inward, said spring-recoil, lead-advancing mechanism adapted to displace said chuck outward for jaw-opening purposes when displaced by pressure to the full longitudinal extent, and gravity-operated means disposed in said casing to obstruct the mechanism when the pencil is held normally and to free the mechanism when the pencil is inverted.

8. In a pencil as claimed in claim 7, a lead-feeding magazine in said spring-recoil lead-advancing mechanism, and means for releasing into

said magazine leads of any one of a plurality of

qualities, said means comprising an elongated hollow cartridge frictionally engaging the magazine at one end so as to move longitudinally therewith and rotatably with respect thereto, partitions arranged in said cartridge to define a plurality of longitudinal lead-storing compartments, the cartridge open at the end adjacent the magazine, and fixed and rotatable gate means disposed transverse the open cartridge end having apertures therethrough adapted to be brought into registration with each other and with a single cartridge compartment when said mechanism is longitudinally displaced by pressure; whereby the leads of any predetermined cartridge compartment may be released into said magazine.

9. In a pencil as claimed in claim 8, said spring-recoil mechanism including a feed tube formed at the end of said magazine opposite to the cartridge and adapted to permit passage of a single lead, a chuck having outwardly-sprung jaws formed at the free end of said tube, means in the casing for compressing the jaws on said feed-tube chuck to grip a lead when the mechanism is released whereby a lead will be driven forward for at least a portion of the stroke of the mechanism when pressed, the casing shaped to release the feed-tube chuck jaws after a portion of the pressure stroke, and spring means urging recoil of lead-advancing mechanism.

10. In a pencil as claimed in claim 9, a shoulder formed on a portion of the lead-advancing mechanism, and said gravity-operated means comprising an obstruction movable in the casing adapted to lie underneath said shoulder and limit movement of the mechanism when the pencil is held normally and to fall out from under the shoulder when the pencil is inverted, whereby when in inverted position the lead-advancing mechanism may be pressed to the full extent of its longitudinal movement in order that the jaws of both said chucks will open and that the leads will be free to return to their cartridge compartment.

11. In a pencil of the type having an elongated axially-bored casing tapered towards the writing end, and a spring-recoil lead-advancing mechanism movable longitudinally within defined limits in said casing, and wherein a lead is advanced by alternately pressing and releasing said mechanism; a chuck slideable in the casing having outwardly-sprung jaws projecting from the tapered end thereof, shoulder projections on the chuck sections normally disposed inside the casing bore so as to urge said jaws into lead-gripping proximity, and spring means urging said chuck inward so as to maintain the said projections inside the casing.

12. In a pencil as claimed in claim 11, said spring-recoil, lead-advancing mechanism adapted to displace said chuck outward for jaw-opening purposes when displaced by pressure to the full longitudinal extent, and gravity-operated means disposed in said casing to obstruct the

mechanism when the pencil is held normally and to free the mechanisms when the pencil is inverted.

13. In a pencil as claimed in claim 12, said 5 spring-recoil means including a lead-feeding magazine, a feed-tube extending towards the writing end from said magazine having longitudinal slots therethrough, said feed-tube connected to said chuck at the inner end of the latter and adapted to pass a single lead thereto, inwardly-sprung lead-gripping jaws projecting rigidly from the casing through said feed-tube slots, and the feed-tube walls at the inner ends of said slots adapted to abut said jaws to urge 10 the latter apart when the mechanism is somewhat advanced longitudinally by pressure; whereby when the mechanism is advanced, the inwardly-sprung jaws are opened to permit passage of lead down to the protruding chuck, and 15 when the mechanism is released to recoil, said inwardly-sprung jaws prevent retreat of the lead and cause the latter to protrude from and be gripped by the withdrawn chuck.

14. In a pencil of the type having an elongated 20 axially-bored casing tapered towards the writing end, and a spring-recoil lead-advancing mechanism movable longitudinally within defined limits in said casing, and wherein a lead is advanced by alternately pressing and releasing 25 said mechanism; a chuck slideable in the casing having outwardly-sprung jaws projecting from the tapered end thereof, shoulder projections on the chuck sections normally disposed inside the casing bore so as to urge said jaws into lead-gripping proximity, and spring means urging 30 said chuck inward so as to maintain the said projections inside the casing, said spring-recoil, lead-advancing mechanism adapted to displace said chuck outward for jaw-opening purposes 35 when displaced by said pressure to the full longitudinal extent, the gravity-operated means disposed in said casing to obstruct the mechanism when the pencil is held normally and to free the mechanism when the pencil is inverted, said 40 spring-recoil mechanism including means connected to said chuck for guiding a lead to the writing end of the pencil, and means for tightly gripping a lead projecting in from the casing wall and adapted to be opened by advance of said 45 guiding means; whereby upon longitudinal advancement of the mechanism by pressure, lead is permitted to pass to the protruding chuck, whilst upon release and recoil of the mechanism, said gripping means prevents retreat of the lead 50 and causes same to project beyond the withdrawn chuck.
